DESIGN FOR A SPOON OR OTHER ARTICLE OF FLATWARE

Howard R. Lott, Lambertville, N. J., assignor to Diamond Silver Company, Lambertville, N. J., a corporation of New Jersey

Application January 26, 1946, Serial No. 126,014

Term of patent 14 years

(Cl. D54—12)

To all whom it may concern:

Be it known that I, Howard R. Lott, a citizen of the United States and a resident of Lambert-ville, county of Hunterdon, and State of New Jersey, have invented a new, original, and ornamental Design for a Spoon or Other Article of Flatware, of which the following is a specification, reference being had to the accompanying drawing, forming part thereof.

Figure 1 is a front elevational view of a spoon or other article of flatware, showing my new design;

Figure 2 is a rear view of the same;
Figure 3 is an enlarged cross-sectional view
taken substantially along the line 3—3 of Figure 1; and

taken substantially along the line 4—4 of Figure 1.

I claim:

The ornamental design for a spoon or other article of flatware, substantially as shown.

HOWARD R. LOTT.
